UNITED STATES PATENT OFFICE.

MOZ MIZRAHI, OF NEW YORK, N. Y.

FLASH-LIGHT AND BATTERY.

1,282,615.

Specification of Letters Patent. Patented Oct. 22, 1918.

Application filed June 5, 1918. Serial No. 238,340.

To all whom it may concern:

Be it known that I, MOZ MIZRAHI, a subject of the Sultan of Turkey, and a resident of the city of New York, borough of Manhattan, in the county and State of New York, have invented a new and Improved Flash-Light and Battery, of which the following is a full, clear, and exact description.

This invention relates to flash lamps and has particular reference to the economical construction of a flash lamp with reference especially to that portion that corresponds to the usual relatively high priced casing.

Among the objects of the invention is to provide a novel construction of dry cell battery and casing, the latter being of cheap material such as straw board or the like, and providing in direct connection with the battery a socket and movable contact members adapting the same for use in place of the usual high priced casing.

Another object of the invention is to construct a dry cell battery having every function possessed by the usual separate battery, but having also connected thereto a lamp socket and contact spring also constructed as to enable me to manufacture and place upon the market a dry cell possessing as a commercial part thereof a suitable jacket adapting it as a complete lamp ready for the lamp bulb. The complete device, except the lamp bulb, being constructed of reliable nature and marketable as a complete useful device at a price not exceeding the usual retail price of a separate battery.

Whereas in the usual practice of flash lamps there is employed a casing having movable contact devices of a relatively high grade and costly nature and such movable contact devices being subject to breakage or becoming out of order and which cannot be repaired by the layman, I provide a complete flash lamp, ready for the lamp bulb, of such materials that although cheap in construction are sufficiently reliable to outlast the battery proper, and so in the event of breakage or damage the greatest loss irrespective of the lamp bulb, will never exceed the price of an ordinary battery.

With the foregoing and other objects in view the invention consists in the arrangement and combination of parts hereinafter described and claimed, and while the invention is not restricted to the exact details of construction disclosed or suggested herein,

still for the purpose of illustrating a practical embodiment thereof reference is had to the accompanying drawings, in which like reference characters designate the same parts in the several views, and in which—

Figure 1 is a perspective view of my improved flash lamp complete.

Fig. 2 is a vertical central sectional view of the same with the switch open, but indicating in dotted lines the switch closed.

Fig. 3 is horizontal section on the line 3—3 of Fig. 2; and

Fig. 4 is a rear elevation of the movable switch button.

Referring now more particularly to the drawings and for the purpose of this specification it will be understood that 10 indicates a dry battery of well known construction and function, the same including two terminals 11 and 12 of conventional nature and to the latter is connected a lamp bulb socket 13.

The base 14 of the lamp bulb coöperates as usual with a contact stud 15 carried by the socket 13, and stud 15 being in position 80 to be engaged by a flexible contact spring 16 connected to the terminal 11 upon the actuation of a slidable button 17 movable along a slot 18 at the back wall of the cover 19 of the battery jacket 20. The button 17 is 85 shown provided with a pair of legs 21 which after passing inward through the slot are bent away from each other so as to hold the button in proper frictional engagement with the slot walls and thence the ends of the legs 90 are bent toward each other so as to lie above the contact spring 16.

As already premised the lid 19 as well as the jacket 20 is made of ordinary box material such as straw board or heavy paper 95 and hence of a relatively cheap construction. The front edge of the cover is provided with a hole 19' which registers with the laterally projecting bore of the socket 13 carried by the battery and having its 100 axis arranged horizontal. It will thus be seen that the lamp which may be of any usual or conventional type or construction when its base is projected inward through the hole 19' into the socket will lock the 105 cover 19 in place.

I wish to emphasize particularly the nature and arrangement of the spring 16. Whereas in the usual structure the corresponding element in the high priced stand- 110

ard casing is required to be made of a superior grade of metal to insure a reasonable degree of reliability, I have found in practice that for the purpose of this invention a narrow strip of cheap tin answers every purpose. The manner of connecting the inner end thereof to the terminal 11 and the form of the spring between the terminal 11 and the stud 15 provide ample flexibility for the operation of the contact spring in the manner indicated. The socket structure is likewise unusually cheap and yet no difficulty is experienced in my practice in insuring as high a degree of reliability of electrical action from this combined battery and casing as is enjoyed in the use or practice of the high priced devices. When the battery becomes exhausted from normal use another may be purchased including the socket and contact devices ready for the introduction of the same or another lamp bulb. Therefore at the price of an ordinary battery I produce a complete lamp, battery and casing.

25 I claim:

1. In a combined flash light and battery, a dry cell battery, a lamp socket fixed to one terminal of the battery with its axis perpendicular to the longer axis of the battery, a 30 spring contact connected to the other terminal, a movable finger piece to actuate the spring, a cover for the battery inclosing the socket and contact spring, said cover having a hole registering with the socket at one 35 side of the battery, and a lamp bulb pro-

jecting through the hole into the socket thereby holding the cover in place.

2. In a device of the character set forth, a dry cell battery having a finished jacket of cheap material of fixed box-like construction, a cover of similar material slidably fitted upon said battery jacket, a lamp socket and a movable contact member for the respective terminals of the battery and located within the cover, the axis of the socket being perpendicular to the direction of application of the cover to the jacket, and said cover having a hole in alignment with the socket for the application of a lamp bulb into the socket, whereby the lamp bulb will hold the cover from accidental removal.

3. In a device of the character set forth the combination of a dry cell battery having a fixed box-like jacket, a cover movably connected to the jacket, a lamp socket permanently fixed to one terminal of the battery and located within the cover, the mouth of the socket being directed laterally toward one side of the cover, the cover having a hole registering with said socket mouth to receive therethrough into the socket the base of a lamp bulb, a spring contact fixed to the opposite terminal battery at the side thereof remote from the socket, the free end of the contact being bent over and toward the bottom of the socket, and a finger piece carried by the cover above the spring contact and movable into contact therewith to complete the circuit.

MOZ MIZRAHI.
